PRECAST CONCRETE MANHOLE BASE SECTION

Edgar L. Nelson, Carmichael, and Herman W. Davis,
Pollock Pines, Calif., assignors to A. Teichert & Son,
Inc., a corporation of California

Filed Oct. 30, 1968, Ser. No. 14,416

Term of patent 14 years

Int. Cl. D25—5

U.S. Cl. D60—2

FIGURE 1 is a top plan view of a precast concrete manhole base section showing our new design;

FIGURE 2 is a diametrical sectional view, the plane of the section being indicated by the line 2—2 in FIGURE 1;

FIGURE 3 is a diametrical sectional view taken on the line 3—3 in FIGURE 1;

FIGURE 4 is a side elevational view, the opposite side being substantially similar in appearance; and,

FIGURE 5 is a bottom plan view.

We claim:

The ornamental design for a precast concrete manhole base section, as shown and described.
